[57] **CLAIM**

The ornamental design for a removable programmable control module with display for irrigation control system, as shown and described.

DESCRIPTION

FIG. 1 is a top front right side perspective view of a removable programmable control module with display for irrigation control system; the broken lines showing a housing are shown for illustrative purposes only;

FIG. 2 is a front elevational view thereof;

FIG. 3 is a rear elevational view thereof;

FIG. 4 is a top plan view thereof;

FIG. 5 is a right side elevational view thereof, the left side being a mirror image thereof; and,

FIG. 6 is a bottom plan view thereof.
